H. G. WARR,

RAIL ANCHOR.

APPLICATION FILED MAY 3, 1920.

1,372,852.

Patented Mar. 29, 1921.

UNITED STATES PATENT OFFICE.

HAROLD G. WARR, OF PARK RIDGE, ILLINOIS, ASSIGNOR TO THE P. & M. COMPANY, OF CHICAGO, ILLINOIS, A CORPORATION OF ILLINOIS.

RAIL-ANCHOR.

1,372,852.

Specification of Letters Patent. Patented Mar. 29, 1921.

Application filed May 3, 1920. Serial No. 378,505.

To all whom it may concern:

Be it known that I, HAROLD G. WARR, a citizen of the United States, residing at Park Ridge, in the county of Cook and State of Illinois, have invented certain new and useful Improvements in Rail-Anchors, of which the following is a specification.

My invention relates to rail anchor devices adapted to resist the tendency of rail-road rails to move longitudinally.

One of the objects of my invention is to provide a novel and improved one-piece rail anchor, made of sheet metal or other suitable material, which will permit the anchor to be bent to its completed form during its application to the rail, and which will maintain a firm grip on opposite edges of rails having base flanges of different contour.

A further and more specific object of the invention is to provide a rail anchor of the above general character which is so formed that the bendable parts, providing a jaw of the anchor, may be readily bent to a position in which they will take a firm grip on the rail, and the parts of the anchor adjacent the bendable portions rigidified so as to resist the tendency of the strains, incident to the application of the device or during service conditions, to distort the device or loosen its grip on the rail.

The invention has for further objects the novel arrangement and construction of parts hereinafter described and claimed for carrying out the above stated objects, and such other objects as will appear from the following specification.

The invention is illustrated in the accompanying drawings, wherein:

Figure 1 is an edge view of a rail anchor constructed in accordance with my invention shown in its applied position on a rail, the base flange of the rail to which the device is applied being shown in section;

Fig. 2 is a plan view of the structure shown in Fig. 1; and

Fig. 3 is a view in perspective of the rail anchor before it is bent to its completed form.

Like characters of reference designate like parts in the three figures of the drawing.

The form of the invention illustrated in the drawing is preferably made of sheet metal and consists of a flat body portion 10, arranged with its flat surface engaging the

under surface of the rail base, and extending across the rail base 11 at right angles to the length of the rail. One end of the body portion of the anchor is bent upwardly and inwardly to provide a hook-shaped jaw 12 which fits over one edge of the rail base. The other end is formed with an upstanding flange 13 which, when the anchor is in its applied position, extends above the opposite edge of the rail base. This flange is formed along its vertical edges with projecting lugs 15, 16, which, before the anchor is bent to its completed form, are normally in alinement with the flange 13 so as to permit the flange to clear the edge 14 of the rail base when the anchor is applied to the base flange of the rail. The device is secured in its operative position by bending the lugs 15, 16 inwardly so that they will engage with the upper inclined surface of the rail base. The lugs are preferably tapered in width and their under surfaces are beveled at 17 so as to conform approximately to the shape of rail base when they are bent to engage therewith. The portion of the flange 13 intermediate the lugs 15, 16 is formed with a rigidifying corrugation 18, which preferably extends around the lower corner of the anchor, as indicated at 19 (Figs. 1 and 2) so as to stiffen the anchor at this point. With this construction, the anchor device may be made of metal of minimum thickness and at the same time avoid outward bending of the flange 13 by the pressure resulting from forcing the lugs 15, 16 upon the inclined surface of the rail base, or by other strains to which the anchor may be subjected during the presence of a creeping pressure on the rail. The lugs 15, 16 being adapted to be bent during the application of the anchor to the rail, permit it to be readily applied to rails having base flanges of different thickness and slightly different width. With this end in view, the angles between the lugs 15, 16 and the body of the flange 13 are filleted at 17 so that the lugs will bend until the fillets make contact with the upper edge of the rail base. A downwardly bent flange 20 provides a tie-abutting member adapted to engage one of the vertical faces of the tie 21. The tie abutment is rigidified by means of a pressed corrugation 22, preferably arranged adjacent one of the jaws, so that the anchor will be skewed in a

horizontal plane during the presence of a creeping pressure, and thereby take a biting hold on the vertical edge of the rail base at the forward and rear corners 23, 23^a respectively, of the jaws 12, 13.

In applying the anchor to the rail, the jaw 12 is hooked over one edge of the base flange of the rail, as indicated in dotted lines in Fig. 1, the portion of the body 10 adjacent 10 the jaw 12 being preferably inclined downwardly, as indicated at 24, to provide a recess for the flange 25 of the rail base when the anchor is in the partially applied position, indicated in dotted lines in Fig. 1. The 15 other end of the anchor is then raised to the full line position and the lugs 15, 16 bent inwardly so as to grip the upper surface of the rail base, as indicated in full lines in Figs. 1 and 2. The jaw 12, being yieldable, may 20 be applied to rails having base flanges of different thickness, and is adapted to grip the upper and lower surfaces of the rail base with spring pressure. The initial grip of the jaw 13 is exerted on the upper and lower 25 surfaces of the base flange, though when the anchor is skewed, as above mentioned, the vertical edges of the jaws 12, 13 will take a hold on the vertical edge of the rail. A reverse movement of the rail, it will be observed, will not tend to loosen the device 30 from the rail.

While I have described my invention in one specific embodiment, it will be obvious that modifications might be made without 35 departure from the spirit of my invention. I therefore do not wish to limit myself to the specific structure as shown and described, except in so far as specific limitations may appear in the appended claims.

40 I claim:

1. A rail anchor comprising a rail engaging jaw adapted to be bent on a vertical line into wedging engagement with the rail in its application thereto.
- 45 2. A rail anchor, comprising a body portion formed with a rail base engaging jaw adapted to be bent on a vertical line to project over an edge of the rail base and into wedging engagement with the rail in its application thereto.
- 50 3. A rail anchor comprising a body portion formed with vertically disposed lugs adapted to be bent over an edge of the rail base and into wedging engagement with the rail in its application thereto.
- 55 4. A rail anchor comprising a body portion formed with vertically disposed lugs adapted to be bent over an edge of the rail base and into wedging engagement with the upper inclined surface of said base.
- 60 5. A rail anchor comprising a body portion formed at one end with a jaw adapted to fit over one edge of the base flange of a rail, and formed at the other end with a lug 65 adapted to be bent on a vertical line, during

the application of the device to the rail, so as to project over the opposite edge of the base flange of the rail.

6. A one-piece rail anchor comprising a body portion formed at one end with a jaw 70 adapted to fit over one edge of the base flange of a rail, and formed at the other end with a lug adapted to be bent on a vertical line, during the application of the device to the rail, so as to project over the opposite 75 edge of the base flange of the rail.

7. A rail anchor comprising a body portion formed at one end with a jaw adapted to grip one edge of the base flange of a rail, and at the other end with a member adapted 80 to be bent to project over the opposite edge of said rail base, said member being formed with a stiffening rib adapted to reinforce the member at its point of jointure with the body portion.

8. A rail anchor comprising a body portion formed at one end with a jaw adapted to grip one edge of the base flange of a rail, and at the other end with a member adapted to be bent on vertical lines to project over 90 the opposite edge of said rail base during the application of the device to the rail, said member being formed with a stiffening rib adapted to reinforce the member at its point of jointure with the body portion.

9. A rail anchor comprising a body portion formed at one end with a jaw adapted to grip one edge of the base flange of a rail, and at the other end with an upstanding member provided at opposite sides with lugs 100 adapted to be bent on substantially vertical lines to project over the other edge of said rail base during the application of the device to the rail, said member being formed with a stiffening rib adapted to reinforce the 105 member at its point of jointure with the body portion.

10. A rail anchor comprising a body portion formed at one end with a jaw adapted to grip one edge of the base flange of a rail, 110 and at the other end with an upstanding member provided with lugs tapered to correspond to the inclined surface of the rail base and adapted to be bent during the application of the device to the rail so as to project over the opposite edge of said rail base.

11. A rail anchor comprising a body portion formed at one end with a jaw adapted to grip one edge of the base flange of a rail, 115 and at the other end with an upstanding member provided with spaced lugs adapted to be bent during the application of the device to the rail so as to project over the opposite edge of said rail base; the portion 120 of said member intervening between said lugs being provided with a rigidifying rib.

12. A rail anchor comprising a body portion formed at one end with a jaw adapted to grip one edge of the base flange of a rail, 130

and at the other end with an upstanding member provided with spaced lugs adapted to be bent during the application of the device to the rail so as to project over the opposite edge of said rail base; the portion of said member intervening between said lugs being formed with a pressed rigidifying rib.

13. A rail anchor comprising a body portion formed at one end with a jaw adapted to grip one edge of the base flange of a rail, and at the other end with an upstanding member provided with spaced lugs adapted to be bent during the application of the device to the rail so as to project over the opposite edge of said rail base; the portion of said member intervening between said lugs being formed with a pressed rigidifying rib which extends around the lower edge of said member.

14. A rail anchor comprising a body portion formed with a jaw adapted to fit over one edge of the base flange of a rail and at the other end with means adapted to be bent during the application of the device to the rail so as to engage with the opposite edge of said rail base, said jaw being formed with a recess adapted to receive the lower edge of said base flange whereby the anchor assumes an angular position when first put on the rail and is raised to its operative position.

15. A rail anchor comprising a body portion formed with a jaw adapted to fit over one edge of the base flange of a rail and at the other end with lugs adapted to be bent during the application of the device to the rail so as to engage with the opposite edge of said rail base, the body portion being provided with a bend which permits the end of the anchor opposite said jaw to assume an initial angular position from which it is sprung during its application to its operative position.

16. A rail anchor comprising a body portion formed with a jaw adapted to fit over one edge of the base flange of a rail, and at the other end with lugs adapted to be bent during the application of the device to the rail so as to engage with the opposite edge

of said rail base; the body portion being provided with a bend adjacent said jaw which permits the end of the anchor opposite said jaw to assume an initial angular position from which it is sprung during its application to effect a spring grip of said jaw on the rail when the device is in its operative position.

17. A rail anchor comprising a body portion formed with a jaw to fit over one edge of the base flange of a rail and at the other end with means adapted to be bent during the application of the device to the rail to engage with the opposite edge of said rail base, said jaw being formed with a recess adapted to receive the lower edge of said base flange formed so that the anchor assumes an angular position when first put on the rail and is bent adjacent said jaw to its operative position.

18. A rail anchor provided with a rail engaging jaw at one end and adapted to be sprung so as to bring the other end into operative position, said other end having a bendable portion adapted to have a wedging engagement with the rail base.

19. A rail anchor provided at one end with a jaw adapted to take a pinching hold on the edge of the rail base, the other end of the anchor being provided with means adapted to be bent so as to have a wedging engagement with the rail base.

20. A rail anchor provided at one end with a jaw adapted to engage one edge of the rail base, the other end of the anchor being provided with a pair of lugs adapted to be bent so as to bring their lower edges into wedging engagement with the other edge of the rail base.

21. A rail anchor provided at one end with a jaw adapted to engage one edge of the rail base, the other end of the anchor being provided with a pair of lugs adapted to be bent so as to bring their lower edges into wedging engagement with the other edge of the rail base, the anchor being formed so that the portion between the ends is strained on application of the device to the rail.

HAROLD G. WARR.
